UNITED STATES PATENT OFFICE.

WILLIAM R. EDELEN, OF CLEVELAND, OHIO, ASSIGNOR TO CHARLES S. SEATON
AND JOHN A. SEATON, BOTH OF SAME PLACE.

UPSETTING-MACHINE.

SPECIFICATION forming part of Letters Patent No. 417,669, dated December 17, 1889.

Application filed August 1, 1889, Serial No. 319,394. (No model.)

To all whom it may concern:

Be it known that I, WILLIAM R. EDELEN, of Cleveland, in the county of Cuyahoga and State of Ohio, have invented certain new and useful Improvements in Upsetting-Machines for Bolts, &c.; and I do hereby declare the following to be a full, clear, and exact description of the invention, such as will enable others skilled in the art to which it pertains to make and use the same.

My invention relates to improvements in upsetting-machines for bolts, &c.; and it consists in certain features of construction and in combination of parts hereinafter described, and pointed out in the claims.

In the accompanying drawings, Figure 1 is a side elevation. Fig. 2 is a plan. Fig. 3 is a front end elevation. Figs. 4 and 5 are elevations in transverse section, respectively, on lines xx and yy , Fig. 1. Figs. 6 and 7 are views in perspective in detail. Fig. 8 is a detail of plate O.

A represents the base or frame of the machine, the same having mounted on the one end thereof steam-cylinder B. The piston-rod B' connects with cross-head B², the latter being adapted to reciprocate on ways a of the bed. The valve-rod b is operated by means of tilting lever b', this lever being fulcrumed at b². The lower end of this lever connects with the upper end of tilting lever C. The latter is fulcrumed at C', and the lower end thereof connects with rod c. The latter in turn connects with hand-lever c', the lever being fulcrumed at c². By operating this hand-lever the valve is shifted to operate the piston of the steam-cylinder. Lever b', near the lower end thereof, has attached an abutment-screw b³, presenting forward, this screw being adapted to engage the cross-head on the rearward stroke of the latter and just in time to shift the valve, so that the piston is at least cushioned and cannot therefore collide with or damage the rear cylinder-head. Lever C has attached a rod C², this rod extending forward and terminating in a hook end C³. This hook near the extreme forward movement of the cross-head is engaged by a corresponding hook B³ of the cross-head, the engagement of

forward in time to prevent the piston from engaging the forward cylinder-head. In case, therefore, the grasping-dies, hereinafter described, should fail to hold the blank firmly, no damage would accrue by reason of the piston moving too far forward.

A' A' are housings or heavy upright side pieces cast integral with bed A and cast integral with end wall A², the latter connecting the side pieces, the end wall being solid, except that it has an opening a² opposite the die, through which opening the blanks are inserted. The housings and bed have external vertical recesses a', in which operate the legs of yoke D, these legs having an easy fit in the recesses, so that the yoke may reciprocate a limited distance endwise.

E E are the dies, the same fitting snugly between the housings, the forward end of the dies abutting end wall A². These dies, for convenience, are of the four-sided variety shown, each face thereof having a recess, and the different recesses being of different sizes to accommodate different-sized blanks. The forward section e of each recess is in diameter adapted to grasp the blank firmly, while the rearward section e' of each recess is larger in diameter, the blanks being upset to fill the enlarged section of the dies. The lower die rests on the bed and the upper die is fastened to yoke D, so that the upper die rises and falls with the yoke, with the head of the yoke resting always on the die.

Above the housings, and resting thereon and firmly bolted thereto, is a heavy cap F. A shaft G extends through a lateral hole in the cap and is journaled therein, and on the ends of this shaft are secured depending links g. The lower ends of these links, by means of lateral studs g', are pivotally connected with the upper ends of links H. The lower ends of links H are pierced laterally for receiving shaft h, this shaft extending through lateral holes d, made in the lower ends of the legs of yoke D. Links g and H constitute toggles, and when the links are in line the yoke is depressed in position, closing the dies E E. When the links are swung forward and out of line, the yoke is of course elevated, thus separating the dies, (see Fig.

5,) such angular position of the toggles being shown in solid lines, Fig. 1, while in dotted lines is shown the position of the toggles and connected mechanism with the dies closed. 5 Connected with studs g' are connecting-rods I , the latter being pivoted at i to rock-arm J , these arms being mounted on shaft J' . This shaft extends through lateral holes in the bed, and inside the latter has mounted thereon 10 arms J^2 . The upper ends of arms J^2 are provided with rollers j , adapted to engage the cross-head. When the cross-head is in its rearward position, arms $J J^2$ stand approximately vertical, in which position of parts 15 the toggle-links are bent forward and the dies are consequently opened. The cross-head, in moving forward, engages roller j and turns arms J^2 forward and downward, thus moving arms J rearward to the position 20 shown in dotted lines in Fig. 1, thereby closing the dies upon the blank and holding the dies closed during the still further forward movement of the cross-head. In case it is desired to make more than one stroke of the 25 machine without opening the dies the following mechanism is provided for holding the dies closed during such extra strokes:

K is a treadle connecting with the lateral arm of bell-crank lever L , the latter being 30 fulcrumed at the elbow thereof. The upright arm of lever L is connected with rod L' , leading to rock-arm l , the latter being fulcrumed at l' . With arm J in position closing the dies, by depressing treadle K arm l is swung 35 under arm J , thus blocking the latter and holding the dies closed, after which the cross-head may be operated without opening the dies. Spring l^2 returns arm l and the treadle to their normal position on removing the 40 pressure from the treadle. For reversing arms J and connected mechanism whereby the dies are opened bent arms M are provided, the same being located inside the bed, to which they are pivoted at m , and having attached springs m' , these bent arms pressing 45 against the front side of arms J^2 . With the rearward movement of the cross-head the tension of the springs m' returns arms $J J^2$ to their upright positions, thereby opening dies 50 $E E$.

N is a standard secured to the bed and provided with cap N' , the cap and standard along the line of union being bored to fit the upsetting-plunger n . The rearward end of 55 the plunger has an enlarged head n' , and the cross-head has a corresponding hammer-head b^3 , these two heads being constructed, preferably, of hardened steel or other suitable metal for giving and receiving hard blows. The 60 forward end n^2 of the plunger fits the enlarged bore e' of the die for upsetting the blank therein. Consequently different plungers are provided for each sized recess e' of the dies, these plungers being readily changed 65 by removing cap N' .

This machine is used for various purposes—for instance, in upsetting the end portion of

bridge-bolts to form an enlarged cylindrical section on which to cut the threads, so that the screw-threaded sections will be equally strong with the other portions of the bolt. The machine is also used for upsetting the blanks to form heads—square, hexagonal, or octagonal, as the case may be—the dies having been recessed accordingly. With the 75 first stroke of the upsetting-plunger fins are likely to be formed where the dies close together, and hence the blank should be turned on its axis before the next blow of the plunger is delivered. For this purpose it is provided as follows:

P is a disk having a large central opening P' , that registers with opening a^2 aforesaid. This disk in the vertical position shown is journaled at the forward end of the machine 85 and serves as a hand-wheel or vertical turn-table. For journaling this disk a plate O is bolted to the forward end of the machine, the plate having inwardly-projecting segmental flanges O' , each segment thereof being a trifle less than a quarter-circle, and these segments having their inner edges undercut. Disk P has corresponding rearwardly-projecting segmental flanges P^2 , the outer edges of which are undercut to fit flanges O' , 95 the two sets of flanges forming a circular dovetail constituting a journal-bearing for the disk. There is just room enough between the opposing ends of flanges O' to enter flanges P^2 , after which by turning disk P in 100 either direction the flanges interlock, and the disk may be rotated nearly a half-turn without disengaging the curved flanges, whereas it is only necessary to rotate the disk a quarter-turn in case of forging square heads. 105 With hexagonal or octagonal heads the blank requires to be turned only a sixth or eighth of a revolution at a time.

The grippers for turning the blank are as follows: $R R'$ are levers fulcrumed in common on stud R^2 , the latter being attached to disk P . The inner ends of these levers are provided with removable jaws R^3 , adapted to grasp the blank, and hence these jaws are changed for different-sized blanks. Links r 115 are pivoted to the respective levers $R R'$, and said links being pivoted together on pin r' they constitute a toggle for opening and closing jaws R^3 , and pin r' extends rearward far enough to serve as a handle with which 120 to operate the toggle by hand or otherwise. A spring r^2 , of the so-called "C" variety, is fastened to the levers, as shown, the tension of this spring tending to hold the jaws open, and consequently when the toggle-links are 125 turned outward a trifle past the central line the action of spring r^2 will open jaws R^3 wide, and in straightening the toggles to close the jaws spring r^2 is of course compressed. Disk P has notches p, p', p^2 , and p^3 on the periphery thereof, and these notches are engaged by tongue S' of spring-actuated lever S , the latter being fulcrumed at S^2 . The free end of the lever is connected by rod s' with treadle 130

S³. By depressing the treadle, lever S is turned down against the action of spring s, and tongue S' is thereby disengaged from its notch.

5 When tongue S' engages notch p, the disk is in its normal position or at the starting-point, and the other notches are arranged, respectively, for turning the disk one-eighth, one-sixth, and one-quarter of a revolution.

10 Disk P is provided with one or more handles P³ for turning the disk by hand on its axis to rotate the blank.

T is a stationary sector having a curved slot T', in which slot operates a bolt for securing stop t. The stop is of the variety shown and is adjusted along the slot of the sector, so that the stop will engage pin r' when the disk shall have been rotated an eighth, sixteenth, or quarter turn, as the case

20 may be, the engagement of the pin and stop causing a deflection of the toggle-links, whereby jaws R³ are opened and the blank released, and this occurs before the closing of the grasping forging-dies E E aforesaid.

25 Openings a² and P' aforesaid are supposed to be opposite the opening of the dies E E when the latter are in position wide open, and consequently when the blank rests on the lower die E the blank is in position some-

30 what below the center of opening a² and opening P'. Before turning the blank between the open dies E E the blank must be raised from off the lower die, and for this purpose lever R is provided with a handle R⁴, by de-

35 pressing which jaws R³ and the blank are elevated the necessary distance to bring the latter in a central position between the open dies E E and in a central position relative to openings a² and P', and consequently the

40 blank when thus elevated is concentric with the axis of disk P, and hence the rotation of the disk does not change the axis of the blank. The latter, therefore, during its rotation remains centrally between the open dies E E.

45 For holding levers R R' in position for elevating the blank during the rotation of the latter there is provided a lever U, pivoted at U' to lever R, so as to turn laterally. The outer end of lever U terminates in a hand-piece U², and the inner end of this lever has a rearwardly-projecting lip U³ for engaging catch V. The catch is shaped substantially like stop t aforesaid, the catch, however, standing at right angles to the stop—that is to say, the catch projects forward and has the incline thereof uppermost, so that in de-

55 pressing the lever R if lip U³ should engage with the catch it would be snubbed back, the lip U³ being thrust under the catch by

60 means, of course, of hand-piece U². Spring u bears against lever U in the direction to hold the lip disengaged from the catch. Lever U has a rearwardly-projecting rub-iron or boss u', that is engaged by one of the toggle-links when the latter are in line, by

65 means of which engagement lever U is held

against the action of spring u in position with lip U³ engaging the catch. When the toggle-links are deflected by means of pin r' engaging stop t, lever U is simultaneously released by means of the engaging-link moving away from boss u', and spring u reverses lever U, thereby releasing lip U³ from catch V, whereupon the gravity of the blank turns down the inner ends of levers R R', whereby the blank is deposited on the lower die E.

70 A bracket W is connected with disk P, this bracket having a vertical slot in which operates the securing-bolt that fastens catch V to the bracket, and by means of the slot the catch is adjusted vertically to bring the blank at the proper elevation when lip U³ engages the catch. This mechanism for turning the blank is omitted in Fig. 1.

75 What I claim is—

1. In an upsetting-machine, the combination, with a stationary die, a reciprocating yoke, a movable die carried by said yoke, and an upsetting-plunger, of toggle-levers connected with said yoke, and mechanism for operating said toggle-levers to reciprocate the yoke and actuate the upsetting-plunger, substantially as set forth. 85

2. In an upsetting-machine, the combination, with suitable frame-work, of a stationary die secured thereon, a vertically-reciprocating yoke, a die carried by the yoke over the stationary die, toggle-levers connected with the yoke, an upsetting-plunger, and means for automatically operating the toggle-levers to reciprocate the yoke and actuate the upsetting-plunger, substantially as set forth. 95

3. In an upsetting-machine, the combination, with dies, toggles for opening and closing the dies, and plunger adapted to upset the blank in the dies, of steam-operated plunger for operating the upsetting-plunger, and suitable connecting mechanism, substantially as indicated, for automatically operating the toggles by the movement of the steam-hammer, substantially as set forth. 105

4. In an upsetting-machine, the combination, with a steam-operated plunger, upsetting-plunger, dies, and toggles for opening and closing the dies, of rock-arms operatively connected with the toggles, such rock-arms being operated in closing the dies by the movement of the steam-plunger in actuating the upsetting-plunger, a blocking device for holding such rock-arms in position closing the die, and a treadle for operating such blocking device, substantially as set forth. 115

5. In an upsetting-machine, the combination, with dies adapted to be opened and closed, of rotating disk having a central opening in front of the dies, and grippers adapted to grasp the blank, such grippers being mounted on the rotating disk, substantially as set forth. 125

6. In an upsetting-machine, the combination, with rotating disk, and grippers mounted thereon, the jaws of the grippers being oppo-

site the forging-holding dies, of toggles connected with the gripper-arms for opening and closing the gripper-jaws, substantially as set forth.

5 7. The combination, with rotating disk, grippers mounted on the disk, and toggles connected with the gripper-arms for opening and closing the gripper-jaws, of spring connected with the gripper-arms for holding the 10 gripper-jaws open, and an adjustable stop for engaging the toggles and thereby opening the grippers when the blank shall have been rotated a predetermined portion of a revolution, substantially as set forth.

15 8. The combination, with rotating disk and

grippers mounted on the disk, such gripper-arms having a common fulcrum, of hand-lever connected with the grippers for raising and lowering the blank, and a catch for holding the grippers in position elevating the blank, 20 such catch mechanism being held in engagement by the toggles in holding the gripper-jaws closed, substantially as set forth.

In testimony whereof I sign this specification, in the presence of two witnesses, this 7th 25 day of June, 1889.

WILLIAM R. EDELEN.
